UNITED STATES PATENT OFFICE.

CHARLES H. STEWART, OF CHICAGO, ILLINOIS, ASSIGNOR OF ONE-HALF TO
EDWARD H. LAKEMAN, OF SAME PLACE.

FLUSH BOX FOR ELECTRIC SOCKETS AND PLUGS.

SPECIFICATION forming part of Letters Patent No. 650,432, dated May 29, 1900.

Application filed January 12, 1900. Serial No. 1,203. (No model.)

To all whom it may concern:

Be it known that I, CHARLES H. STEWART, a citizen of the United States, residing at Chicago, in the county of Cook and State of Illinois, have invented certain new and useful Improvements in Flush Boxes for Electric Sockets and Plugs, of which the following is a specification.

This invention relates to improvements in boxes or receptacles to be placed in the floor, wall, or ceiling, so as to be flush therewith and to receive and retain electric sockets and plugs; and it consists in certain peculiarities of the construction, novel arrangement, and operation of the parts thereof, as will be hereinafter more fully set forth, and specifically claimed.

The principal object of my invention is to provide a box or receptacle which when in place will be flush with the surface of the floor, wall, or ceiling or other surface in which it is located and so the exposed surface of the box or receptacle may be given the same color or finish as the surface in which it is embedded.

Another object of the invention is to so construct it that access to the plug or socket may be readily attained.

Other objects and advantages will appear in the description hereinafter contained.

In order to enable others skilled in the art to which my invention pertains to make and use the same, I will now proceed to describe it, referring to the accompanying drawings, in which—

Figure 1 is a view in side elevation, partly in section, showing the box in position in a floor or wall and illustrating by dotted lines the position of the doors when access to the interior of the box is desired. Fig. 2 is a vertical sectional view taken on line 2 2 of Fig. 1, showing one of the doors by dotted lines in its raised position and illustrating the socket and plug in elevation. Fig. 3 is a plan or face view of the box with the doors thereof closed, and Fig. 4 is a similar view showing the doors open.

Similar letters refer to like parts throughout the different views of the drawings.

A represents a box or receptacle which is made of any suitable size, form, and material,

but preferably cylindrical, as shown. This box or receptacle may be located in a suitable opening *a* in the wall, floor, and ceiling *B*, or other surface, so that its upper or outer portion is a slight distance below the exterior thereof. To the upper portion of the box *A* is secured, by means of screws *c* or otherwise, a plate *C*, which may be of any desired material and form, but preferably rectangular, as shown in the drawings, and is provided with a central opening *c'* for the reception of the doors *D*, which are pivotally secured on pintles *d*, located in the plate *C*, near the side edges of its opening.

The lower surface of the plate *C* is provided with extensions *c*², through which the screws *c* are passed to secure the plate to the box. This plate is also provided with horizontal extensions or ledges *c*³, which extend slightly inward from the perimeter of the opening in the plate and serve as supports for the doors. These doors are provided at about the middle of their adjacent edges when closed with enlargements *d'*, having openings *d*² to receive suitable insulating-pieces *d*³, which are also provided with openings *d*⁴ for the reception of the conductor *E*, which is connected at one of its ends to the electric plug *F*, the other conductor *E'* being connected to the socket *F'*, which plug and socket may be of the ordinary or any preferred kind.

By reference to Figs. 2, 3, and 4 of the drawings it will be seen that the insulating-pieces *d*³ are countersunk in the adjacent edges of the doors *D* and may be held in position by means of rivets *d*⁴ or otherwise. The lower outer portions of the doors *D* are cut away, as at *e*, (see Fig. 4,) to furnish more room when it is desired to reach the plug *F* with the fingers or an instrument while the doors are in their raised position. One of the doors is usually provided with a recess *e'* in one of its ends for the reception of the finger-nail or an instrument to be used when it is desired to open the doors, and for this purpose the outer surface of the plate *C* is also provided with an indentation or recess *e*², communicating with the recess *e'* when the door is closed.

From the foregoing and by reference to the drawings it will be seen and clearly understood that by using a box of the above-de-

scribed construction the exposed surface of the plate C and the doors D may be given any desired finish, so as to correspond with the finish of the surface in which they are located, 5 and that when the box is in position access to its interior may be readily attained for the purpose of inserting or removing the socket and plug or for making the electric connections. It is also apparent that by using the 10 divided doors, hinged so as to open from each other, the connection with the plug may be easily made and that when the box is in position there will be no projection from the floor or wall.

15 Having thus fully described my invention, what I claim as new, and desire to secure by Letters Patent, is—

1. The combination with a box or receptacle having one of its ends open, of a plate secured 20 to the open end of the box and having a central opening and provided on its lower surface with horizontal and inward extensions or ledges, doors pivotally secured near their outer edges to the plate so as to close the open-

ing therein and to rest on said ledges and to open from each other, said doors having recesses in their adjacent edges, and insulating material located in said recesses and carried by the doors, substantially as described.

2. The combination with a box or receptacle 30 having one of its ends open, of a plate secured to the open end of the box and having a central opening and provided on its lower surface with downward extensions and also with horizontal and inward extensions or ledges, 35 doors pivotally secured near their outer edges to the plate so as to close the opening therein and to rest on said ledges, said doors having recesses in their adjacent edges and cut-away portions in their lower outer portions, and insulating material located in said recesses and carried by the doors, substantially as described.

CHARLES H. STEWART.
